Clifton L. Dorland
BY *Victor J. Evans*

ATTORNEY

UNITED STATES PATENT OFFICE.

CLIFTON L. DORLAND, OF STRATFORD, ONTARIO, CANADA.

ROTARY TOOTH-BRUSH.

1,279,996.

Specification of Letters Patent. Patented Sept. 24, 1918.

Application filed September 12, 1917. Serial No. 191,092.

To all whom it may concern:

Be it known that I, CLIFTON L. DORLAND, a subject of the King of England, residing at Stratford, in the Province of Ontario and 5 Dominion of Canada, have invented new and useful Improvements in Rotary Tooth-Brushes, of which the following is a specification.

This invention relates to new and useful 10 improvements in tooth brushes, and the principal object of the invention is to provide a circular brush with means for giving it a rotary motion.

Another object of the invention is to provide 15 a casing for inclosing the brush but having a cut-away portion through which part of the brush projects.

A further object of the invention is to provide 20 a handle part connected with the brush and combining with means for rotating the same and including means for disengaging the parts.

Another object of the invention is to provide 25 a device of this character which is simple and durable in construction, reliable and efficient in operation and one which can be manufactured and placed upon the market at a minimum cost.

The invention also consists in certain 30 other features of construction and in the combination and arrangement of the several parts, to be hereinafter fully described, illustrated in the accompanying drawings and specifically pointed out in the appended 35 claims.

In describing my invention in detail, reference will be had to the accompanying drawings wherein like characters denote like or corresponding parts throughout the 40 several views, and in which:

Figure 1 is a side elevation with the parts broken away.

Fig. 2 is an end view.

Fig. 3 is a cross section on line 3-3 of 45 Fig. 1.

Fig. 4 is a side view of the brush head.

Fig. 5 is a detail of one of the disks.

In these views 1 indicates the casing preferably of cylindrical shape and having its 50 lower part cut-away as at 2 and exposing the bristles 3. The outer end of said casing is provided with a depression 4 for receiving the end of the shaft 5 on which the brush head 6 is mounted, the other end of 55 said shaft being supported in the manner to be hereinafter described. The brush

head is composed of the rings of bristles 3 which are supported by the disks 7, said parts being secured together in any desired manner. The inner end of the casing is 60 closed by a removable disk 8 which is provided with a flange 9 fitting in the end of the casing and removably held therein by means of the notches 10. Said disk is provided with an opening 11 through which the 65 stem 12 of the handle 13 passes, said stem being provided with an enlargement 14 which engages the outer face of the disk and prevents the stem from entering too far into the casing. A cylindrical member 15 has 70 an opening in one end thereof to engage the end of the stem 12 and a screw 16 holds said stem within the opening. The other end of the member 15 is provided with a bayonet slot 17 which receives a transverse 75 pin 5' in the end of the shaft 5. The stem 12 is provided with spiral ribs 18 and said stem passes through a plate 19 secured to the end of the handle 13 which is provided with a recess 20 for receiving the said stem. Said plate is provided with grooves for engaging the ribs so that when the stem is moved with relation to the plate said ribs will cause the stem to rotate. The end of the casing is provided with corrugations 21 80 for forming a hand-hold when the brush is being used. And to prevent the edges of the casing from injuring the lips I bend said edges inwardly as at 22.

When the brush is to be used the casing 85 is held with one hand with the projecting part of the brush against the teeth. The handle is then grasped by the other hand and moved longitudinally in both directions so that the stem is forced in and out of said 90 handle whereby the ribs thereon engaging with the grooves in plate 19 will cause the stem to rotate and thus rotate the brush. The brush may be easily cleaned without removing the stem from the casing as the 95 cleansing water has free access to the casing through the cut away portion therein, but if it is desired to separate the parts of the device this may be easily and quickly done by removing the disk 8 so as to separate the brush from the stem whereby said 100 brush may be removed from the casing.

It is thought from the foregoing description that the advantages and novel features of my invention will be readily apparent. 105

I desire it to be understood that I may make slight changes in the construction 110

and in the combination and arrangement of the several parts, provided that such changes fall within the scope of the appended claims.

5. What I claim is:—

1. A tooth brush comprising a casing having an opening therein, a brush head rotatably supported in said casing, a removable disk closing one end of said casing, a handle having a stem passing through said disk, a member detachably connecting said stem with the brush, and means for rotating the brush by a longitudinal movement of the handle.
10. 2. A tooth brush comprising a casing

having an opening therein, a brush head having one end journaled in the end of the casing, a member detachably connected with the other end of the brush head, a removable disk closing one end of said casing, a handle 20 having a stem passing through said disk, means for detachably connecting the end of said stem with said member and means for rotating the brush by a longitudinal movement of the handle.

In testimony whereof I affix my signature.

CLIFTON L. DORLAND.
